COMBINED COAT HANGER AND HAT RACK

Charles H. Kraft, Mission Woods, Kans.

Application December 6, 1954, Serial No. 33,417

Term of patent 7 years

(Cl. D33—8)

Fig. 1

Fig. 3

Fig. 1 is a side elevational view of a combined coat hanger and hat rack, showing my design.

Fig. 2 is a top plan view thereof, and

Fig. 3 is a front elevational view thereof.

I claim:

The ornamental design for a combined coat hanger and hat rack, as shown.
